ELECTRIC MOTOR CONSTRUCTION
 Cecil G. Young, Warren, Ohio, assignor, by mesne assignments, to H. K. Porter Company, Inc., Pittsburgh, Pa., a corporation of Delaware
 Filed May 23, 1959, Ser. No. 815,540
 6 Claims. (Cl. 103—87)

My invention relates to electric motors, more particularly to an electric motor combined with a pump, and the principal object of my invention is to provide new and improved products of this character.

The motor of my invention, and the pump combined therewith, are notable in construction in that no packing joint is provided on the shafts of either the motor or pump and this is advantageous because of the known unreliability of packing joints. Accordingly, the construction of my invention may be referred to as a hermetic pump motor and is characterized by the fact that the pump casing is connected directly with the motor casing and the interiors of the two are in communication.

My invention relates to an electric motor having a "canned" stator and rotor and embodies a novel bearing construction which maintains concentricity of the motor parts despite wear in the bearings. The motor and pump combination, at least in part because of the foregoing advantages, is ideally suited for pumping fluids of a toxic, precious, corrosive, or like nature, because losses through the shaft seal of the prior art is avoided.

In the drawings accompanying this specification and forming a part of this application, there are shown, for purposes of illustration, several embodiments which my invention may assume and in these drawings:

FIGURE 1 is a central longitudinal sectional view through a motor-pump combination illustrating an embodiment of my invention,

FIGURE 2 is an enlarged, fragmentary sectional view of parts disclosed in FIGURE 1, and

FIGURE 3 is a central longitudinal sectional view through a motor-pump combination illustrating another embodiment of my invention,

Referring particularly to FIGURES 1 and 2, the embodiment therein disclosed comprises an electric motor 10 and a pump 11. The pump, as herein disclosed, comprises a volute housing 12 having a central inlet 14 and a peripheral discharge (not shown).

An impeller 15 of any suitable design is disposed for rotation within the pump housing 12 and has a hub 16 adapted to be suitably connected to one end of the motor shaft 17. The impeller 15 has a tubular forward portion 18 through which fluid is drawn by the impeller 15 from the inlet 14 and is discharged, by action of the impeller, under pressure through the pump discharge.

Wearing rings 19 and 20 are disposed respectively between the impeller hub 16 and pump housing and between the impeller portion 18 and pump housing. The wearing rings are usually pressed into seats formed in the pump housing and provide a close clearance with the impeller to restrict recirculation of the fluid between pump outlet and inlet. In the present embodiment, the rings 19 and 20 are formed of carbon.

In the embodiment herein disclosed, the pump housing 12 has a concentric extension 21 integrally connected to an end plate 22, the latter being connected in fluid-tight relation with an end plate 23 which comprises a part of the casing of motor 10. The end plate 22 has a circular opening in which a plate 43 is held, as by bolts 44. The plate 43 has a circular central opening for the close passage of a tubular bearing support 25, the latter having a large inner opening at one end and a smaller opening at the impeller end. The smaller

2

opening has a stepped surface for receiving the bearing 19.

The exterior surface of bearing support 25 at its impeller end carries a band 26 to which is welded, or otherwise suitably secured, a plate 27 which forms a defining wall of the pump housing 12. The band 26 may be removably held to the support 25 by set screw (not shown) or in any other suitable manner. The plate 27 is provided with a plurality of openings 28 for the passage of pumped fluid from the impeller housed portion of the pump housing to a rather large space 29 formed by the plate 27, the plate 43 and the peripheral wall 21, and the plate 27 confines turbulence of fluid to the zone near the impeller for improved hydraulic efficiency.

The motor 10, as herein illustrated, comprises a cylindrical shell 30 and end plates 31 and 32, the end plates respectively fitting opposite ends of the shell by means of stepped connections 32. A plurality of tie bolts 33 (only one visible in FIGURE 1) pass through openings in the end plates 31 and 31, the bolts having a head bearing against the outer surface of the plate 31 and an extremity threaded into the opening in plate 23, to tightly draw the end plates against opposite ends of the shell 30.

An auxiliary end plate 34 is bolted against the outside surface of the plate 31, and a tubular bearing support 35 is welded, or otherwise suitably secured, to the plate 34 and extends from opposite sides thereof.

A laminated stator 36, and field coils 37 are supported within the shell 30, the stator having a central opening 38 and a stator shell 39 passes through such opening and extends from opposite sides of the stator. The stator shell may be formed of any suitable material to accomplish the function of "canning" the stator and, in cases where corrosive fluid is pumped, the stator shell is preferably formed of stainless steel.

As seen in FIGURES 1 and 2, opposite ends of the stator shell closely pass through central openings in the end plates 23 and 31. Each end plate has an outwardly directed circular rib 40 which is welded, as seen at 41, to the respective end of the stator shell 39 to thus seal the stator laminations 36 and the windings 37 against contact with any fluid which may enter the interior of the stator shell 39.

The auxiliary end plate 34 has an inwardly directed circular rib 42 (see FIGURE 2) which closely fits within a circular recess formed in the end plate 31 for the purpose of accurately locating the end plate 34 in centered relation with the axis of the motor.

The end plate 23 has a welded connection with the adjacent end of the stator shell 39 in like manner and this end plate has an annular recess in its outwardly facing side to receive a circular rib on plate 43 which forms a side wall of the chamber 29. Bolts 44 are provided for detachably connecting the plates 34 and 43 to their respective end plates 31 and 23. The plate 43 has a plurality of openings 45 to meter fluid flow from the chamber 29 to the interior of the stator shell 39.

A laminated rotor 50 is connected to and carried by the motor shaft 17, and a cylindrical rotor shell 51 closely encompasses the rotor 50 and is utilized to "can" the rotor, that is, to shield it from contact with fluids within the stator shell 39.

Bearing means are disposed between the motor shaft 17 and the motor casing, and, as herein illustrated, each bearing means comprises a frustum-shaped member 52 and a cooperating bearing member 53 which has a conical recess closely receiving the inclined side wall of the respective frustum-shaped member 52. Each member 52 is firmly fixed to the shaft 17, as by a press fit, or by welding, so that the connection therebetween is fluid tight.

Each member 52 as best seen in the left hand member illustrated in FIGURE 2, is formed with an out-

wardly directed circular rib 54 which closely fits within the respective end of the rotor shell 51 and is welded thereto, as shown at 55. The shell 51 is preferably made of stainless steel when the fluids pumped are of a corrosive nature. As best seen in FIGURE 2, the outer diameter of the rotor shell 51 is slightly less than the inner diameter of the stator shell 39 to maintain a very small air gap and operating clearance which, in the present case is about .020 inch.

With the small operating clearance between the stator and rotor shells, it is essential that the stator and rotor be maintained concentric despite bearing wear, and the tapered bearings herein illustrated maintain such concentricity, as will be apparent from the present and subsequent description.

The bearing member 53 at the right hand side of FIGURE 1 has a cylindrical exterior which closely fits within the larger inner opening of the tubular support 25 and has a flat bottom bearing against a flat transverse wall of the support. A pin 60 seating within aligned openings in the flat bottom and transverse wall may be utilized to insure that the bearing member 53 is held against rotation within the tubular support.

The bearing member 53 at the left hand side of FIGURE 1 has a cylindrical exterior which closely but slidably fits within the interior of bearing support 35. A cylindrical backing plate 61 also closely but slidably fits within the bearing support and has a flat transverse surface which bears against a flat surface of the bearing member 53. A pin 62 fitting within aligned openings in the backing plate and bearing member may be utilized to insure that the latter is held against rotation within its support. The bearing plate 61 may be formed with an elongated slot 63 which receives a pin 64 carried by the bearing support 35 to hold the bearing plate against rotation.

To insure proper fit between the bearing surfaces of the two pairs of bearing members 52, 53, the members are spring pressed to maintain bearing fit despite bearing wear. Since the bearings have conical bearing surfaces which are initially disposed concentric with the motor shaft, bearing wear is taken up by relatively moving cooperating bearing members 52, 53 in an axial direction and toward each other.

In the presently disclosed embodiment, the backing plate 61 has a central recess 65 which receives one end of a coil spring 66. The opposite end of the spring is received within a cap 67 secured to an inner end of a rod 68. The outer end of the tubular bearing support 35 is closed by a transversely extending disc 69 which is welded or otherwise suitably secured to the support. The rod 68 extends through a packing gland 70 carried by the closure disc 69 and its outer extremity bears against the end of an adjusting stud 71.

The stud 71 is threaded through an opening in a support plate 72 and a plurality of screw studs 73 hold the plate 72 in spaced relation from the disc 69. It will be appreciated that the urging force of the spring may be varied by adjustment of the adjustment stud 71. In some cases, the adjustment for the spring 66 may be omitted and a spring of known force interposed between the backing plate 61 and a transverse stop fixed within the bearing support 35. In some cases it may be desirable to indicate or observe bearing wear and for that purpose a rod 75, or the like, may have one end bearing against the backing plate 61 and its opposite end extending through a packing gland 76 carried by the closure disc 69. The outer extremity of the rod 75 may carry suitable measurement indicia 77 which may be noted from time to time to record bearing wear.

From the foregoing, it will be evident that the bearing member 53 (left hand side of FIGURE 1) is urged against its cooperating frustum-shaped member 52. Since the members 52 are rigidly secured to the motor shaft 17, the entire rotor assembly is urged to the right, as

viewed in FIGURE 1, and therefore the right hand frustum-shaped member 52 is urged into bearing engagement within the conical recess in the corresponding member 53. Thus, despite bearing wear, concentricity of the various motor parts is maintained.

The bearing parts 52, 53 are preferably of dissimilar materials and, in the present embodiment, the members 53 are formed of carbon and the members 52 formed of stainless steel since these materials form ideal cooperating bearing members which have long life and require little maintenance and lubrication. The fact that the bearing members 53 are closely received within their respective bearing supports 25 and 35 is important since the members 53 are protected against fracture which might otherwise be brought about by the axial pressure on the bearings.

Since my invention provides a hermetically connected pump and motor, and since the motor has a "canned" rotor and stator, pumped fluid may be safely circulated through the motor to cool it and under certain circumstances provide lubrication for the bearings.

In the presently disclosed embodiment, a portion of the pumped fluid from the impeller housing is passed through openings 28 and 45 to the interior of the stator shell 39 and fills the space 80 adjacent the right hand bearing assembly. Any fluid which passes from space 80 downwardly along the conical bearing surfaces may flow along the exterior surface of the shaft 17 and return to the low pressure area at the center of the pump impeller through openings 81 in the hub of the impeller, and because of the differential in pressure a tendency to circulate fluid in this path is induced, although the bearings may not always, if at all, permit such circulation of fluid.

The fluid from space 80 may also pass through the operating or air gap between the stator shell 39 and rotor shell 51 and pass to a similar space 82 adjacent to the left hand bearing assembly. At this latter assembly, fluid may pass along cooperating bearing surfaces and escape through a central opening 83 in the bearing plate 61 to the space 84 within the tubular bearing support 35. However, a greater portion of the fluid from space 82 flows through a pipe 85 which has one end communicating with the space 82 and its other end communicating with the space 84. An exhaust pipe 86 may convey fluid from the space 84 back to the inlet 14 of the pump 11.

The embodiment of my invention shown in FIGURE 3 is somewhat similar to that previously described, certain distinctions being that two pumps are adapted to be driven by respective opposite ends of the motor shaft and that Belleville washers are used to spring-load each bearing assembly. Apart from the distinctions, corresponding parts will be designated in the embodiment of FIGURE 3 by the same reference numerals supplemented by the suffix "a."

The motor shaft 17a in this embodiment supports an impeller 15a at each end (only one impeller being shown in FIGURE 3) and such impeller rotates within a housing 12a as before. The metering and support plates 43a are bolted to respective end plates 23a and are maintained concentric by having a circular periphery closely fitting a circular recess in the respective end plate.

A cylindrical bearing support 90 is welded to each plate 43a interiorly of the motor casing and a collar 91 is welded to each support plate 43a exteriorly of the motor casing. Each collar 91, as before, supports a plate 27a.

A bearing member 53a is closely received within each bearing support 90 and has a flat protective washer 92 bearing against its flat transverse surface. Pins 93, 94 may be used to hold the bearing members 53a against rotation. A series of Belleville spring washers 95 is interposed between each washer 92 and the adjacent flat surface of respective collar 91, each Belleville spring as-

sembly urging its bearing member to engagement with the cooperating bearing member 52a.

In the embodiment disclosed in FIGURE 3, the springs at opposite ends of the shaft provide for shaft thrust in either direction which may result from different pumping conditions at the two pumps. It will be noted that the rotor 50a is wider than the stator 36a to maintain proper operating relations between the two regardless of the fact that the shaft 17a which carries the rotor has shifted axially a slight amount due to any unbalance in pumping conditions. As before, the bearing members 52a are preferably of stainless steel to resist corrosion and the bearing members 53a are of carbon since this material is inert and non-corrosive, is capable of withstanding high temperatures, and is unaffected by acids, alkalis and the like, and contains nothing which will dissolve or otherwise separate therefrom. It will be appreciated that the bearing members 52, 53 may be made of any materials suitable for and required by the characteristics of the fluid being pumped.

It is presently preferred to use the Belleville spring as the urging force maintaining the bearings in proper relationship because of the characteristics of such springs. For example, a desirable characteristic of Belleville springs is that once the spring washer (or washers) approach a flat condition, the spring rate becomes substantially constant, thereby giving substantially constant spring force generally independent of position. This is very desirable from a bearing loading standpoint.

As before, pumped fluid is permitted to circulate through the motor and the latter has a "canned" rotor and stator to protect these parts from the fluid.

With pumping pressures equal in both pumps, fluid from either casing 12a will pass through openings 28a. Since the pressures are equal, no fluid flow will exist in the gap between the stator and rotor shells 39a and 51a. Accordingly, fluid flow is induced along the bearing surfaces to return through the opening in the impeller hub and back to the respective pump inlet.

It may be preferable to have different pressures at the two pumps so that fluid flow is induced from the pump of higher pressure, through the motor and to the pump of lower pressure. However, in this instance, care must be taken to pump fluids which may be mixed. In some cases, it may be desirable to provide small lubrication grooves in either the member 52 or member 53 to facilitate flow of fluid through the bearing.

In view of the foregoing it will be apparent to those skilled in the art that I have accomplished at least the principal object of my invention and it will also be apparent to those skilled in the art that the embodiments herein described may be variously changed and modified, without departing from the spirit of the invention, and that the invention is capable of uses and has advantages not herein specifically described; hence it will be appreciated that the herein disclosed embodiments are illustrative only, and that my invention is not limited thereto.

I claim:

1. An electric motor, comprising a housing including a tubular shell and end plates closing opposite ends of said shell, a cylindrical sleeve extending longitudinally within said shell and having its opposite ends connected to respective end plates and providing a sealed tubular space between the outer surface of said sleeve and the interior surface of said shell, a pair of tubular bearing supports each rigidly secured to and extending from a respective end plate, a conically recessed bearing mounted within each bearing support with the recesses facing each other, at least one of said bearings being movable axially within its support, the rigid securing of said bearing supports and the mounting of said bearings cooperating to maintain said bearings in spaced alignment on a common axis which is coaxial with the axis of said cylindrical sleeve, a rotor concentric with and located within said sleeve for rotation therein, said rotor having an outer cylindrical surface slightly smaller than the inner surface of said sleeve

to provide an annular gap therebetween of very small magnitude to separate the rotor from said sleeve and stator and yet provide a free flux path for efficient transmission of magnetic flux from said stator to said rotor, oppositely facing cone-shaped journals on and coaxial with said rotor and fitting complementarily within respective conical recesses, and resilient means for urging said cone-shaped journals and the surfaces defining said conical recesses together in coaxial manner so that any bearing wear is coaxial with said rotor and thus will not affect concentricity of the latter with respect to said cylindrical sleeve and thereby maintain said annular gap.

2. The construction according to claim 1 and further including a pump casing joined to said motor housing, and means establishing free flow of the pumped fluid from said pump casing to the interior of said cylindrical sleeve.

3. The construction according to claim 2 wherein an end of said cylindrical sleeve opens into said pump casing, and a plate spans such open end and has metering openings therein to provide a regulated flow of material from said pump casing to said sleeve interior.

4. The construction of claim 1 wherein both of said bearings are movable axially within their tubular supports and wherein Belleville washers press each of said bearings against respective cone-shaped journal surfaces of said rotor.

5. An electric motor-pump unit, comprising a motor housing including a tubular shell and end plate means closing opposite ends of said shell, a cylindrical sleeve extending longitudinally within said shell and having opposite ends sealed to respective end plate means, at least one of said end plate means having an opening communicating with the interior of said sleeve, a motor stator within the space between the exterior of said sleeve and the interior of said tubular shell, a motor rotor concentric with and located within said sleeve for rotation therein, said rotor having an outer cylindrical surface slightly smaller than the inner surface of said sleeve to provide an annular gap therebetween of very small magnitude to separate the rotor from said sleeve and stator and yet provide a free flux path for efficient transmission of magnetic flux from said stator to said rotor, a pair of tubular bearing supports within said sleeve, each rigidly connected to and extending inwardly of respective end plate means, a bearing mounted within each bearing support, each bearing having a conical recess coaxial with said cylindrical sleeve, at least one of said bearings being movable axially within its support, and said conical recesses facing each other, the rigid securing of said bearing supports and the mounting of said bearings cooperating to maintain said bearings in spaced alignment on a common axis which is coaxial with the axis of said cylindrical sleeve, oppositely facing cone-shaped journals fixed on and coaxial with said rotor and fitting complementarily within respective conical recesses, resilient means for urging said cone-shaped journals and the surfaces defining said conical recesses together in coaxial manner so that any bearing wear is coaxial with said rotor and thus will not affect the concentricity of the latter with respect to said cylindrical sleeve, thereby maintaining said annular gap, a pump casing having an open back wall connected in fluid-tight relation with said one end plate means and communicating with the interior of said sleeve through the opening in said one end plate means, an impeller within said pump casing, said rotor having a shaft which extends through said one end plate means and into said pump casing and to which said impeller is secured.

6. The construction of claim 5 wherein both of said end plate means have an opening therein communicating with the interior of said sleeve at respective opposite ends thereof, and wherein an open back pump casing is connected in fluid-tight relation with each end plate means, each pump casing having communication with the interior of said sleeve through the opening in the

respective end plate means and thereby with each other through said sleeve, an impeller within each pump casing and said rotor having shafts extending from opposite ends, each shaft extending through a respective end plate means and into a respective pump casing for connection to the impeller within the latter.
